**DEVICE FOR CRUCIBLE-FREE OR FLOATING-ZONE
MELTING A CRYSTALLINE ROD, ESPECIALLY A
SEMICONDUCTOR ROD**

My invention relates to device for crucible-free or floating-zone melting a crystalline rod, especially a semiconductor rod, and more particularly to such device having a flat-wound induction heating coil annularly disposable about the rod and provided with hollow leads.

Flat coils are frequently employed as energy sources in crucible-free zone-melting operations. By flat coils it has been meant heretofore and is furthermore meant herein coils having one winding or several windings disposed in a plane. Such flat coils have an advantage over conventional coils having a cylindrical configuration in that they produce very slight axial extension or stretching of the molten zone formed in the crystalline rod in the course of the zone-melting process. This results in an increased stability of the molten zone, which is especially important for rods of relatively large cross section.

A disadvantage of the use of a flat coil for crucible-free zone melting is that due to the sharply defined limits of the molten zone produced thereby, the temperature gradient in the adjacent solid regions of the crystalline or semiconductor rod is relatively high. A frequent consequence thereof is the formation of dislocations in the crystalline structure of the rod.

It is accordingly an object of my invention to provide heating device for crucible-free zone melting a crystalline rod which, on the one hand, limits the length of the molten zone in the direction of the rod axis and, on the other hand, maintains a relatively low-temperature gradient in the adjacent solid portions of the crystalline rod on both sides of the molten zone.

With the foregoing and other objects in view, I provide, in accordance with my invention, in a device for floating-zone melting a crystalline rod, a flat-wound induction heating coil adapted to encircle a crystalline rod so as to maintain a molten zone therein, and a slotted hollow member of electrically conductive material disposed coaxially to the flat-wound coil in close coupling therewith, the hollow member having an axial length many times greater than that of the flat-wound coil.

The magnetic force lines passing through the opening of the flat-wound coil cannot therefore close on themselves right at the outer edge of the flat-wound coil but must rather traverse the entire length of the space within the hollow member before being able to complete their circuit at the outside thereof. Thus, the hollow member acts as a preheating or postheating device i.e., it reduces the temperature gradient on one or both sides of the molten zone. The effect produced by this leveling-off of the temperature gradient with the device of my invention is superior to that resulting from conventional preheating or postheating devices in the form of radiant heating members or additional induction heating coils that are either separately energized or are energized by induction from the main molten zone heating coil.

In accordance with a further feature of my invention, the flat coil is disposed in the axial center of the hollow member so as to obtain thereby a preheating and a postheating effect substantially of equal value.

In accordance with yet another feature of my invention, the flat coil is disposed either closer to the upper or the lower end of the hollow cylinder, so that a substantially vertically held rod may be selectively subjected either to a respective intensified postheating or preheating effect.

Other features which are considered as characteristic for the invention are set forth in the appended claims.

Although the invention is illustrated and described herein as embodied in device for crucible-free or floating-zone melting a crystalline rod, especially a semiconductor rod, it is nevertheless not intended to be limited to the details shown, since various modifications and structural changes may be made therein without departing from the spirit of the invention and within the scope and range of equivalents of the claims.

The construction and method of operation of the invention, however, together with additional objects and advantages thereof will be best understood from the following description of specific embodiments when read in connection with the accompanying drawing, in which:

FIG. 1 is a perspective view of the heating device for crucible-free floating-zone melting of a crystalline rod according to my invention;

FIG. 2 is a top plan view of FIG. 1;

FIG. 3 is a longitudinal sectional view of FIG. 1 taken along an axial plane thereof; and

FIG. 4 is a longitudinal sectional view similar to that of FIG. 3 of another embodiment of the heating device of my invention showing a modified form of hollow member flaring frustoconically outward from both sides of the flat-wound coil.

Referring now to the drawing, and first particularly to FIGS. 1 to 3 thereof, there is shown a flat coil 1 having a single winding. The flat coil 1 has an opening 2 of adequate cross section for accommodating a nonillustrated crystalline rod such as of semiconductive material like silicon, for example. The flat coil 1 is surrounded by an annular slotted hollow member 3 having a substantially cylindrical shape. Advantageously, in accordance with my invention the flat-wound coil 1 and the hollow member 3 are rigidly connected to one another for example by welding, brazing or soldering. Terminals or junctions 4 are provided for supplying electrical current as well as coolant flow to the hollow member 3 and flat coil 1. The terminals 4 are formed of finlike projections 4a for carrying electric current, and tubular members 4b located adjacent or fixed to the finlike projections 4a for circulating coolant medium, such as water, to the flat coil 1 and hollow member 3. The flat coil 1 is located substantially at the axial center of the hollow member 3, which is provided on both sides of the flat coil 1 with observation slots or peepholes 5 and 6. In order to keep the scatter or stray field as small as possible at these locations, the observation slots 5 and 6 are made as small as possible. The length of the observation slots 5 and 6 corresponds substantially to the thickness of the semiconductor rod being processed. This is necessary for examining the diameter of the rod portion recrystallizing from the molten zone. The hollow member 3, as well as the flat-wound coil 1, are formed of thin copper sheets whose edges are appropriately welded, brazed or soldered together. The hollow interior of the flat coil 1 and the hollow member 3 is traversed by cooling medium, such as water, entering through one of the tubes 4b and leaving through the other of the tubes 4b. The flat coil 1 shown in the figures is formed of a single winding lying in one plane but may also be formed of several windings disposed in a single plane. The single winding of the coil 1 in the illustrated embodiment has a width measured in the plane of the coil 1 that is greater than the thickness thereof measured in the axial direction of the coil 1. To obtain the least possible inductivity, it is desirable that the flat-wound coil 1 have an outer diameter to inner diameter ratio of at least 1.5. Especially favorable conditions are attained when the ratio of outer to inner diameter of the flat coil 1 is about 2.0 to 1 or 2.5 to 1. In order to maintain a narrow molten zone while simultaneously cooling the flat-wound coil 1 intensively, it is advantageous to provide the coil 1 with an outer peripheral edge 7 which is of greater thickness measured in the axial direction of the coil 1 than the thickness of the inner peripheral edge 8 thereof (FIG. 3).

In order to achieve a gradual heat transfer also to the portions of the rod that are very far removed from the molten zone, I provide, in accordance with my invention, another embodiment of the heating device wherein, as shown in FIG. 4, the hollow member 3' is in the form of a frustum of a cone flaring outwardly to its base in axial direction from both sides of the flat-wound coil 1. It is also possible, for example, to have the portion of the hollow member 3 located below the flat coil 1, as shown in FIG. 4, in cylindrical form whereas the upper portion thereof is frustoconical as illustrated in FIG. 4 or to have the upper hollow member portion cylindrical and the lower one frustoconical.

In addition to the advantage of reducing the thermal gradients on both sides of the molten zone of a crystalline rod being zone-melted, the invention of this application also affords the advantage that the hollow member 3 has a relatively high reflective action. Reflective losses of the molten zone can thereby be largely avoided. The flat coil 1 and the hollow member 3 are formed of material having relatively good electrical conductivity, such as copper or silver for example.

The device of my invention can be employed preferably for carrying out crucible-free floating-zone melting processes in a protective gas atmosphere, such as of hydrogen. Due to the relatively low inductivity of my device, the voltage drop in the induction heating coil device of my invention is relatively low so that the danger of an electric flashover between the induction heating coil device and the crystalline or semiconductor rod being processed is minimal. The increased levitating action of the induction heating coil device of my invention is also of special advantage. This is particularly important for the so-called compression of the rod i.e., in a zone-melting operation wherein the recrystallizing rod portion has a greater diameter than the rod portion supplied to the molten zone.

To further elucidate the invention of the instant application, the dimensions of a particular embodiment are as follows, considered in connection with FIGS. 2 and 3 of the drawing:

Inner diameter of the flat coil	$d_f=29\text{mm.}$
Outer diameter of the flat coil	$d_o=70\text{mm.}$
Axial length or thickness of the flat coil at the inner periphery	$h_1=2\text{mm.}$
Axial length or thickness of the flat coil at the outer periphery	$h_2=6\text{mm.}$
Axial length of the hollow member	$h_3=60\text{mm.}$

Although the induction heating coil device according to my invention can be employed with particular advantages for performing crucible-free floating-zone melting processes in a protective gas atmosphere, for example of hydrogen, a noble or inert gas or a mixture of hydrogen and a noble or inert gas, the use of my inventive device is not limited to these processes. Thus, the device of my invention can also be used to advantage for carrying out a crucible-free floating-zone melting process in vacuo. Furthermore, the device of my invention can also be employed for performing zone-melting processes such as are disclosed, for example, in German Pats. 1,128,413 and 1,218,404.

I claim:

1. In a device for floating-zone melting a crystalline rod, a flat-wound induction heating coil adapted to encircle a crystalline rod so as to maintain a molten zone therein, and a slotted hollow member of electrically conductive material disposed coaxially to said flat-wound coil, said flat-wound coil

having an outer edge directly connected to said hollow member, said hollow member having an axial length considerably greater than that of said flat-wound coil.

2. Device according to claim 1 wherein said flat-wound coil is located substantially at the axial center of said hollow member.

3. Device according to claim 1 wherein said hollow member has a substantially cylindrical shape.

4. Device according to claim 1 wherein said hollow member is frustoconical and flares outwardly from said flat-wound coil in the axial direction thereof.

5. In a device for floating-zone melting a crystalline rod, a flat-wound induction heating coil adapted to encircle a crystalline rod so as to maintain a molten zone therein, and a slotted hollow member of electrically conductive material disposed coaxially to said flat-wound coil in close coupling therewith, said hollow member having an axial length considerably greater than that of said flat-wound coil and comprising a pair of frustoconical portions respectively flaring outwardly from opposite sides of said flat-wound coil.

6. Device according to claim 1 wherein said heating coil is formed with a single flat winding having a width in the radial direction of said coil that is greater than the thicknesses of said winding at the inner and outer peripheries thereof.

7. In a device for floating-zone melting a crystalline rod, a flat-wound induction heating coil adapted to encircle a crystalline rod so as to maintain a molten zone therein, and a slotted hollow member of electrically conductive material disposed coaxially to said flat-wound coil in close coupling

30 therewith, said hollow member having an axial length considerably greater than that of said flat-wound coil, said heating coil being formed with a single flat winding having a width in the radial direction of said coil that is greater than the thicknesses of said winding at the inner and outer peripheries thereof, the thickness of said winding at said outer periphery thereof being greater than at said inner periphery thereof.

8. In a device for floating-zone melting a crystalline rod, a flat-wound induction heating coil adapted to encircle a crystalline rod so as to maintain a molten zone therein, and a slotted hollow member of electrically conductive material disposed coaxially to said flat-wound coil in close coupling therewith, said hollow member having an axial length considerably greater than that of said flat-wound coil, said flat-wound coil and said hollow member forming an integral double-walled structure having a hollow space between the respective double walls thereof, and including circulating means communicating with said hollow space for circulating cooling medium therethrough.

9. Device according to claim 1 wherein the flat-wound coil and the hollow member are formed of an electrically conductive metal selected from the group consisting of copper and silver.
